UNITED STATES PATENT OFFICE

WILLIAM C. SCHEU, OF GRAND JUNCTION, COLORADO, ASSIGNOR TO THE BAINISTER
ORCHARD HEATER COMPANY, OF GRAND JUNCTION, COLORADO, A CORPORATION
OF COLORADO.

ORCHARD-HEATER.

1,089,013.

Specification of Letters Patent.

Patented Mar. 3, 1914.

Application filed June 17, 1912. Serial No. 704,237.

To all whom it may concern:

Be it known that I, WILLIAM C. SCHEU, a citizen of the United States, residing at Grand Junction, in the county of Mesa and 5 State of Colorado, have invented a new and useful Orchard-Heater, of which the following is a specification.

This invention relates to means for furnishing heat to orchards to protect the same 10 from the effects of frost or freezing weather, and particularly to that class of orchard heaters which are adapted for burning oil, for example, crude oil, slop distillate or other cheap oil.

15 The main object of the present invention is to provide an oil burner which will burn fuel of the stated character in such manner as to produce a maximum amount of heat with the minimum amount of smoke or 20 smudge, the protective action of the burner being based on its heating effect and not on the smudge produced thereby. In many cases, particularly in lemon orchards, the production of smudge or smoke is objectionable as it impairs the appearance of the 25 fruit and by providing for combustion of the fuel in such manner that substantially no smoke is produced, the objectionable effects of this smudge are avoided and at 30 the same time, the fuel is utilized with maximum economy in the production of heat.

An important feature of the present invention is the provision of means for preliminary vaporization of the oil before combustion, the heater comprising a vaporizing chamber into which sufficient air is admitted to generate by its combustion, the required 35 amount of heat for vaporization of the oil, this vapor being conducted away from the 40 generating point and mixed with a further quantity of air for complete combustion thereof.

Another object of the invention is to provide means for regulation of the amount 45 of air admitted to the vaporizing or generating chamber, so as to govern the amount of vapor generated and thereby vary the heating effect of the burner in accordance with the requirements.

50 Another object of the invention is to provide an air supply means for the generating or vaporizing chamber which will maintain a supply of air when said regulating means is turned off, so that there will always be

sufficient air admitted to the said chamber 55 for starting the burner in operation.

Another object of the invention is to so construct the heater that the various parts thereof may be nested for storage or shipment.

Other objects of the invention will appear hereinafter.

The accompanying drawings illustrate embodiments of my invention, and referring thereto: Figure 1 is a vertical section 65 of the heater with the cover plate removed. Fig. 2 is a plan view of the complete heater. Fig. 3 is a side elevation thereof. Fig. 4 is a detail section of a form of joint between the chimney and cover. Fig. 5 is a section on line x^5-x^5 , Fig. 2. Fig. 6 is a side elevation partly in section, of a different form of the heater. Fig. 7 is a section on line x^7-x^7 , Fig. 6. Fig. 8 is a vertical section of another form of the heater.

Referring to Figs. 1 to 3, the heater comprises a pot or base portion 1, forming a receptacle for the oil, this pot being of any suitable shape, being, for example, round and flared upwardly so that a large number of pots may be nested for storage or shipment. A cover or top member 2 is provided for said pot, preferably formed as a frusto conical member of sheet iron or other suitable material, and having at its lower 80 edge a flange 3 for fitting the upper edge of the pot 1, either inside or outside thereof, the said member 2 being formed at its upper end with an opening 4 for communicating with the chimney 5. Any suitable means 85 may be used for connecting the chimney to the member 2, for example, as shown in Fig. 1, the member 2 may have an upwardly extending flange 4' formed by drawing or bending the upper edge of said member 2 95 and the chimney 5 may have its lower edge formed as shown at 5', so as to fit closely and tightly on said flange 4, whereby the chimney is secured in position on the member 2 and an airtight joint is maintained. 100 Or, as shown in Fig. 4, the chimney may be secured to the cover by rivets 6'. By means of the flange 3 and the said joint between the member 2 and the chimney, the space within the pot 1 and cover 2 is maintained 105 in substantially airtight relation with respect to the outer air, so that air can not enter except through the air inlet means

hereinafter described, this space within the pot and below the cover, forming a generating or vaporizing chamber, and the air inlet means being such that only sufficient air is admitted to this chamber to provide by its combustion, the necessary heat and vaporization of the oil.

The air inlet means may consist of a plate 8 formed as a casting or forging, fitted to the frusto conical face of the member 2 and secured to said member by suitable means such as rivets 8', said plate 8 being provided with a plurality of air inlet openings 9 and with a starting opening 10, said openings in the said plate registering with openings 9' and 10' in the member 2. The metal around the air inlet openings in the cover member is preferably bent up into the openings in the plate as shown at 2', to give a watertight joint. A closure member or damper plate 11 is movably mounted on the plate 8, for example, by being pivoted thereto as shown at 11' so as to wholly or partially close one or both of the openings 9, the plate 8 being cut away above the opening 10, as shown at 12, so that said opening 10 is never closed and air may enter therethrough for starting the burner in operation, even when the damper plate 11 is in closed position. Said damper plate 11 extends over the plate 8 at each end so as to shed water and is provided at its outer end with a perforation 13 to facilitate operation of the damper plate by means of a suitable implement, and said damper plate is provided at its upper edge with an upturned flange 14 and at its lower edge with a downturned flange 15 to assist in shedding water.

The chimney 5 is preferably round and may be flared upwardly as shown in Fig. 1, said chimney being provided, for example, at its upper portion with openings 6 for admission of air, said holes being provided in any desired number and in any desired arrangement, for example, in a single row. A cover plate 27 may be provided for the chimney, said cover plate having a downturned rim 28 extending over the upper edge of the chimney, so as to prevent rain from entering the chimney, it being understood that this cover plate is removed when the burner is in operation.

The construction above described may be variously modified without departing from the invention, for example, the flange 3 on the cover member 2 may be made to extend on the inside of the pot 1, as shown in Fig. 6, instead of on the outside, as shown in Fig. 1. The air inlet openings for the vaporizing chamber may be located in the side of the pot 1 and may be closed by a sliding valve plate 26 guided in ways 26', see Fig. 6, and the recess 12 may be omitted, as shown in this figure, so that all the openings may be closed. The chimney or stack may

be formed as an upwardly tapering pipe, as shown at 18, in Fig. 6, and in this case, it may conveniently be connected rigidly to the cover, indicated at 19, for example, by means of a seam 20, this construction enabling the chimney and cover member to be nested together, whereas in the form shown in Fig. 1, the chimney and cover member will be detached and nested separately, or as shown at 21 in Fig. 8, the chimney may be made of cylindrical form and may be provided with an outwardly flaring flange 22 at its upper edge having perforations 23 for admission of air. The air inlet means may be provided at a plurality of places distributed around the cover member as indicated at 24 in Fig. 8. It is advantageous to form the chimney or stack so that it begins at the top of the cover member 2 and extends upwardly therefrom, as such construction provides a continuous chamber or passage for flow of the vapor from the generating or vaporizing chamber to the stack, without retarding or impeding its movement.

A lid is preferably provided for the heater to cover the stack or chimney when the heater is not in use, so as to prevent rain from entering. In case a flaring chimney such as shown in Figs. 1 to 3 is used, the said lid is preferably of the form shown at 27, being provided with downturned inwardly bent flanges 28 which fit the sides of the chimney, this flange being on three sides, leaving the fourth side open, so that the lid may be shoved onto the chimney from one side, and the flanges 28 will engage with the chimney to hold the lid firmly in position and prevent it from being dislodged by wind. In case a tapering chimney is used, the lid may consist of a round plate shown at 30 in Fig. 6, with a downturned flange 31 fitting around the chimney and covering the holes therein.

The operation is as follows: The lid 27 being removed, oil is poured into the pot 1, for example, to nearly the full depth of said pot. At the time of starting, a little gasoline or distillate may be poured into the pot and ignited by a torch, and sufficient heat is thereby produced to start the heater in operation, the air entering through the opening 10 causing combustion of a portion of the vapor in the vaporizing or generating chamber, the heat produced in this manner, being sufficient to generate vapor from the body of oil contained in the pot 1 in sufficient quantity for the continuous operation of the burner until the said body of oil is consumed. In this connection the location of the air inlet means in the conical cover member 2 is of advantage in that it calls for the incoming air to be directed obliquely downward toward the body of oil, so that the resulting flame approaches toward the oil. This vaporizing flame is in normal op-

eration; confined to the surface adjacent to the air inlet and does not pass out through the chimney so that unconsumed hydrocarbon vapor passes upwardly from the vaporizing chamber through the opening 4 into the stack or chimney 5, and that portion of the vapor which passes the openings 6 is mixed with a further quantity of air and consumed thereby, the quantity of air so admitted to the vapor being sufficient to produce complete combustion. By moving the damper plate 11 so as to open the openings 9 more or less, an additional amount of air may be supplied so as to increase the size 15 of the generating flame and proportionately increase the heat developed and the amount of vapor generated passing up through the chimney or stack. By this means the magnitude of the flame at the top of the stack 20 may be varied with corresponding variation in the amount of heat produced by the burner, but it will be understood that the regulation of the air admitted through the air inlet openings 9 in this manner is limited 25 to the amount required for generation so that the final combustion takes place in or above the stack and the two zones of flame, viz., the generating flame and the complete combustion flame are kept separate and distinct in the normal operation. In consequence of this operation the combustion effected in the burner is that of hydrocarbon vapor and not of oil, the oil being first vaporized and then burned in distinction to the action of a flame in contact with and rising from the surface of the body of oil. It will, however, be understood that when 35 the air inlet openings are opened wide and the flame is operating at maximum intensity, the generating flame may extend up into the stack and merge into the flame therein.

What I claim is:

1. An orchard heater comprising a pot for receiving oil, a cover for the pot having 45 a flange engaging the edge of the pot to make a tight joint therewith, said cover extending upwardly in the form of a frustum of a cone and having a central opening and

a chimney extending upwardly from the upper end of said cover and communicating 50 with said opening, said chimney having lateral air inlet openings, air inlet means opening into the space inclosed by the cover, and means for restricting admission of air through said air inlet to produce combustion 55 in the said space, with sufficient resultant heat to vaporize the oil, the air inlet openings in the chimney being of sufficient capacity to provide for complete combustion 60 of the vapor so generated.

2. An orchard heater comprising a pot, a frusto conical cover member provided with a flange making a tight joint for said pot, and having a central opening, a chimney communicating with said opening and extending upwardly therefrom, and making a tight joint with said cover, said chimney having lateral air inlet openings, said cover being provided with air inlet openings, and a closure member for regulating the amount 65 of opening of said air inlet openings in the cover.

3. An orchard heater comprising a pot, a cover member provided with a flange making a tight joint with said pot, and having 75 a central opening, a chimney communicating with said opening and extending upwardly therefrom and making a tight joint with said cover, said chimney having lateral air inlet openings, a plate on said cover, said 80 plate being provided with a plurality of openings, a closure member movably mounted on said plate to close one or more of said openings, said plate being spaced from the closure member adjacent to one of said openings to maintain continual communication 85 with the outside air through said opening, irrespective of the position of the closure member.

In testimony whereof, I have hereunto set my hand at Los Angeles, California this 12th day of June, 1912.

WILLIAM C. SCHEU.
